G. W. URMSON,
ADJUSTABLE JAMB FOR FOLDING PARTITIONS.
APPLICATION FILED MAR. 1, 1916.

1,203,437.

Patented Oct. 31, 1916.

UNITED STATES PATENT OFFICE.

GEORGE W. URMSON, OF JERSEY CITY, NEW JERSEY.

ADJUSTABLE JAMB FOR FOLDING PARTITIONS.

1,203,437.

Specification of Letters Patent. Patented Oct. 31, 1916.

Original application filed November 24, 1915, Serial No. 63,194. Divided and this application filed March 1, 1916. Serial No. 81,346.

To all whom it may concern:

Be it known that I, GEORGE W. URMSON, a subject of the King of England, residing at Jersey City, in the county of Hudson, State of New Jersey, have invented certain new and useful Improvements in Adjustable Jams for Folding Partitions, of which the following is a full, clear, and exact specification.

10 This invention relates to adjustable jams especially designed for folding partitions in order to allow for swelling and shrinkage of the wooden sections of the partition and always insure the proper closing or expansion of said partition. Without adjustable jams, the swelling of the sections will prevent them from being fully extended into line, at least one pair of the hinged sections being left buckled or projecting laterally from the line, while if allowance is made for swelling, the sections will not completely fill the opening when the wood shrinks. To overcome this condition, I provide adjustable jams of improved construction which may be retracted when the wooden sections of the partition are swollen, and which may be extended when the sections shrink, so that a precise fit of the partition between the jams may always be had.

15 Another object is to provide improved means for detachably securing the partition to the adjustable jamb whereby said partition can only be separated from the jamb when open.

20 A further object is to prevent the hinge jamb from being adjusted when the partition is connected thereto.

25 The invention will be first hereinafter described in connection with the accompanying drawings, which constitute a part of this specification, and then more specifically defined in the claims at the end of the description.

30 In the accompanying drawings, wherein similar reference characters are used to designate corresponding parts throughout the several views: Figure 1 is a broken elevation of the partition in closed position. Fig.

35 2 is a horizontal section of the partition and jams taken on the line II-II of Fig. 1. Fig. 3 is a fragmentary view of the upper end portion of the hinged edge of the par-

tion, showing the opening for the introduction of an instrument for withdrawing 55 or retracting the spring pressed hinge pin. Fig. 4 is a horizontal section through the hinge jamb, showing the portion in open position, and Fig. 5 is a detailed view of one of the filling plates. 60

Referring more particularly to the drawings, 1 designates the adjustable hinge jamb, that is, the jamb to which the adjacent section 4 of the partition is hinged, and 2 is the opposite jamb against which the outer 65 end section 5 of the partition is adapted to fit when the partition is closed.

The adjustable hinge jamb 1 is detachably connected to the permanent jamb strip 12 by means of a screw 13, Figs. 2 and 4, of 70 which there may be any desired number suitably spaced apart from the bottom to the top of the jamb as indicated in Fig. 1. The jamb 1 is arranged between molding strips 14 which are secured to plates 15 by 75 screws 16, while said plates are fastened to the jamb strip 12 by screws 17. It will be understood that as many of the plates 15 as are necessary or desirable may be used, preferably the same number as there are screws 80 13 being employed, one of said screws passing through the central portion of each plate. The plates 15 have outwardly projecting pins 18 which engage correspondingly shaped sockets 19 in the inner face of 85 the jamb 1. These pins 18 serve to support a variable number of filling plates 20, each of which has a central opening 22 for the passage of the screw 13, and other passages 21 to fit over said pins 18, see Fig. 5. By 90 varying the number of the filling plates 20 placed between the plates 15 and the jamb 1, said jamb may be retracted or projected to a sufficient extent to counteract any swelling or shrinkage of the partition, so as to 95 always insure the complete closing and proper fit of the partition when closed as shown in Figs. 1 and 2. The jamb 2 may be adjusted in a similar manner with respect to the permanent jamb strip 120 by 100 means of screws 130 and a variable number of the filling plates 20.

The outer face of the jamb 1 is concave, as at 23 to provide a close fit with the rounded or convex inner edge 24 of the partition section 4 which is detachably hinged 105

to the jamb 1 so that it may be taken off to permit access to the screws 13 when it is desired to change the number of filling plates 20 between the jamb 1 and the plate 15.

As illustrated best in Figs. 1 and 3, the detachable hinge connection between the sections 4 of the partition and the adjustable jamb 1 comprises straps or plates 25 secured 10 to the upper and lower end portions of said jamb, and spring pressed hinge pins 26 carried by the upper and lower ends of the section 4 of the partition. Springs 27 normally hold the pins 26 projected so as to 15 engage suitable openings in the straps 25. The pins 26 have lateral projections 28 arranged in passages 29 opening on the inner rounded edge 24 of the section 4 of the partition.

When the partition is open, as illustrated in Fig. 4, the pins 26 may be withdrawn from engagement with the straps 25 by inserting a suitable instrument, such as a nail, into the passages 29 and thereby forcing the projections 28 toward the springs 27. 20

25 The outer edge of the free end section 5 of the partition is preferably provided with a groove 53 to fit over a tongue 54 on the jamb 2 for preventing sight being had through the juncture of these parts. It will 30 be understood that the folding partition may consist of any desired number of sections between the hinged section 4 and the outer section 5, and that disregarding the adjustable jamb 2, the remainder of the structure 35 herein described may be used on an ordinary hinged door as well as a folding partition.

This application is a division of my former pending application for folding partition filed November 24, 1915, Ser. No. 63,194.

40 Having thus described my invention, what I claim as new and desire to secure by Letters Patent of the United States is:

1. The combination with a permanent jamb strip, of an adjustable jamb, filling 45 plates interposed between the jamb and jamb strip, projections on the jamb strip to support a variable number of said filling plates, and means for detachably securing the jamb to the jamb strip and clamping 50 the filling plates between them, whereby said jamb is rigidly held in adjusted posi-

tion against movement toward or away from said jamb strip.

2. The combination with a permanent jamb strip, of plates secured to said strip 55 and having outward projections, an adjustable jamb of less width than said plates disposed across the same intermediate of their lateral edges, filling plates interposed between the jamb and the plates secured to 60 the jamb strip and supported on said projections, means for detachably securing the jamb to said jamb strip, and molding strips secured to and covering the lateral edge portions of the first mentioned plates which 65 project at either side of the jamb for housing the filling plates.

3. The combination with an adjustable jamb of detachable securing means for the jamb and a door hinged to the jamb, the 70 hinged edge of the door preventing access to said securing means when the door is mounted on its hinges and in either open or closed position.

4. The combination with an adjustable 75 jamb having a concave outer face, of removable means for securing said jamb in adjusted position, said securing means being accessible for adjustment only in the concavity of the outer face of the jamb, and a 80 door hinged to the jamb and having its inner edge convex to fit the concavity in the jamb, and prevent access to said jamb adjusting means when mounted on its hinges and in either open or closed position. 85

5. The combination with an adjustable jamb having a concave outer face, of removable means for securing said jamb in adjusted position, said securing means being accessible for adjustment only in the 90 concavity of the outer face of the jamb, horizontal straps projecting beyond the concave face at the upper and lower ends of the jamb, a door detachably hinged to said straps and having a convex inner edge to 95 fit the concavity in the jamb, and prevent access to said jamb adjusting means when mounted on its hinges and in either open or closed position.

In testimony whereof I have signed my 100 name to this specification.

GEORGE W. URMSON.
